UNITED STATES PATENT OFFICE

THOMAS A. DICKS, OF PITTSBURGH, PENNSYLVANIA, ASSIGNOR TO PITTSBURGH SCREW & BOLT CORPORATION, OF PITTSBURGH, PENNSYLVANIA, A CORPORATION OF PENNSYLVANIA

AIR COLLECTOR FOR PROPELLERS

Application filed April 23, 1931. Serial No. 532,201.

This invention relates to airplane propellers, and in particular to a device for collecting and directing air through the hub of the propeller.

It is well known that the deafening noise created by a whirling propeller is caused by air rushing into a partial vacuum which is formed along the trailing edge of the blade by the whirling motion itself. Several propellers have been designed heretofore in which air was exhausted along the trailing edge of the blade so as to neutralize the vacuum, and consequently, to decrease the noise thereof. In my pending application, Serial No. 499,511, filed December 2, 1930, I disclosed one type of propeller constructed and designed to overcome this deafening noise and also to increase the efficiency of the propeller in which air is drawn through ports in the hub and is discharged along the trailing edge of the blade. In that application I relied upon the Venturi effect set up in the blade by air passing across openings on the trailing edge thereof and also on centrifugal force, to draw the air through the hub into the blade.

It is an object of the present invention to provide an air collector for positively forcing air through the blade of a propeller to neutralize the vacuum formed along the trailing edge of the blade so as to decrease the noise and materially increase the efficiency of the propeller.

Another object of this invention is to provide an air collector which may be applied to any type of propeller hub.

A further object of this invention is to provide an air collector for forcing air into the hollow blades of an airplane propeller which is relatively simple in construction, relatively cheap to manufacture and readily applied to the propeller.

These and other objects which will be made apparent to those skilled in this particular art are accomplished by means of this invention, one embodiment of which is described in the following specification and illustrated in the accompanying drawings, wherein;

Figure 1 is a view in front elevation of a

propeller hub having an air collector secured thereto.

Fig. 2 is a view partially in section taken on line II—II of Figure 1.

Fig. 3 is a view in section taken on line III—III of Fig. 2.

Fig. 4 is a view in perspective of the hub and air collector shown in Figure 1.

Fig. 5 is a view in front elevation of a propeller hub and an air collector showing a modification of my invention.

Fig. 6 is a view in side elevation of the hub shown in Figure 5 having a portion thereof broken away for convenience of illustration.

Fig. 7 is a view in section taken on line VII—VII of Fig. 6.

Fig. 8 is a view in perspective of the hub and air collector shown in Figure 5.

Fig. 9 is a view in front elevation of a propeller hub and air collector embodying another modification of my invention, and

Fig. 10 is a view in side elevation of the hub shown in Figure 9 having a portion thereof broken away for clearness in illustration.

In the several figures of the drawings, like characters refer to like portions of the structure.

Referring now to Figures 1, 2, 3, and 4 of the drawings in detail, 10 designates a hub provided with a transverse axial sleeve 11 in which the drive shaft is adapted to be secured in any appropriate or well known manner. Integrally formed on the hub portion 10 are annular sockets 12, each of which is provided with relatively thickened portions 13, adjacent the hub portion through which a bolt 14 of the usual type extends for fastening the shank of a blade 15 in the socket.

The sockets are also provided with clamping lugs 16 on the outer ends thereof through which bolts extend for clamping the socket securely around the end of the bolt. The shank 15 of the blade is provided with a notched portion 17 which registers with a port 18 formed in the wall of each of the sockets 12. The ports 18 are formed on the leading face of the sockets 12, that is, the ports face in the direction of rotation of the

hub and not the direction of travel of the plane.

When the propeller is whirling at a high rate of speed, air is drawn into the blade through the registering ports 17 and 18 and is discharged into the partial vacuum formed along the trailing edge through slots formed along the trailing edge of the blade (not shown). The air drawn through the ports 18 in the sockets 12 tends to neutralize the vacuum and decrease the noise of the whirling of the propeller.

So that air will be positively forced through the ports into the blades, I provide an air collector or ring which directs the air through the ports 17 and 18 and forces the same into the blade where it is discharged along the trailing edge. The air collector comprises a cup-shaped member 20 which is secured to the sockets of the hub and which faces in the direction of travel of the plane so that the member will collect air when the plane is in motion and force the same into the blades through the ports 17 and 18.

The walls of the cup-shaped member 20 are cut away at 21 for receiving and partially enclosing the sockets 12 when the air collector or ring is secured to the hub. The base 22 of the bottom of the cup-shaped member 21 is of channel shape, as shown in Figure 3, for receiving the thickened portions 13 formed on the sockets 12. The base is also provided with an opening (not shown) through which the sleeve 11 extends when the air collector 20 is positioned on the hub. It is apparent that such a construction permits the collector to fit snugly against the hub 10 and sockets 12 so as to form pockets for collecting the air on each side of the hub adjacent the ports 18. The cup-shaped member 20 is secured to the sockets by the bolts 14 which extend through openings formed in the base 22 of the member.

In Figures 5, 6, 7, and 8, I have illustrated a hub construction which differs from the construction of the hub heretofore explained in that the bolts 14 which secure the blades 15 in the sockets 12 extend through the sockets 50 at right angles to the axial sleeve 11, while the ports 18' which are formed in the walls of the sockets 12, face in the direction of travel of the plane and not in the direction of rotation of the propeller.

The air collector or ring for directing and forcing air through the ports 18' in this modification, comprises an annular base member 30 having a wall portion 31 formed around the periphery which collects and holds the air on the base member. In order that the air collector may fit snugly against the hub, the base 30 is provided with a trough 32 of the same contour as the annular sockets 12 which receives the sockets 60 when the air collector is positioned on the

hub. The trough 32 extends diametrically on the base and is provided with a series of openings, one of which receives the front end of the hub portion 10 while the other openings, designated as 33, register with the ports 18' in the sockets 12. The air collector is held in position on the front end of the hub by the bolts 14 which extend through openings formed in legs 34 depending from the base member 30 on the opposite sides of the trough 31. When the plane is in motion air is collected in the base member 30 by the walls 31 which extend outwardly from the base member in the direction of travel and is forced by the oncoming air through the ports 33, 18' and 17 into the blades where it is exhausted along the trailing edge.

In Figures 9 and 10 I have illustrated another modification of my invention in which an air collector is applied to an assembled hub 41 which is secured together by bolts 42. The hub 41, when assembled, has the usual transverse axial sleeve 43 for securing the hub to the drive shaft of the motor and radially extending sockets 44 which receive shanks 45 of the propeller blades. The blades are retained in the sockets by shoulders 46 extending inwardly from the inner face of the sockets 44 which engage shoulders 47 formed on the shanks 45 of the blades. A clamping ring 48 positioned around the outer end of each of the sockets 44 securely lock the blades to the hub.

Each of the sockets is provided with an opening 49 adjacent the base thereof which faces in the direction of travel of the plane and which registers with an opening 50 formed in the shank 44 of the blade. The outer ends of the blade used in this modification, as in the previous modifications having slots formed along the trailing edge thereof through which the air forced into the blades through the openings 49 and 50 is discharged into the partial vacuum. The air collector for positively forcing the air through the openings 49 and 50 into the blade, comprises an annular base portion 51 having a wall 52 around the outer edge thereof. So that the collector may be secured to the annular surface of the sockets 44, the base portion 51 is provided with troughs 53 which receive the sockets when the air collector is positioned on the hub. The air collected on the annular portion 51 is forced through openings 54 which are formed in the trough and registers with the openings 49 in the sockets. The collector is held on the hub by the bolts 42 which extend through a centrally located thickened portion 55 formed on the base portion 51.

From the foregoing description, it is readily apparent that I have designed a device which collects and positively forces air into the blades where it is exhausted along the trailing edge of the blade, neutralizing the

vacuum, and consequently decreasing considerably the noise of the propeller, and increasing the efficiency of the propeller.

It is to be understood that the invention is not limited to the constructions herein specifically illustrated but can be embodied in other forms without departing from the spirit of the invention or the scope of the appended claims.

10. What I claim as new and desire to secure by Letters Patent is:

1. In a propeller, the combination with a hub having a series of annular blade receiving sockets extending radially therefrom, of a member secured to said sockets having an annular wall extending beyond said hub so as to direct air into said propeller through registering openings in said member and said sockets.

20. 2. The combination with a propeller hub, having a series of radially disposed sockets extending from said hub each having a port therein, of a member secured to said hub having curved wall portions thereon extending around said sockets so as to form pockets adjacent said ports for collecting air and directing it through the ports.

30. 3. An air collector for forcing air into a propeller hub having radially disposed blade receiving sockets provided with ports on the leading face thereof, comprising a cup-shaped member secured to said hub, and having the walls thereof extending around said sockets so as to form air pockets adjacent the ports therein.

40. 4. An air collector for forcing air into an airplane propeller hub having a series of radially extending sockets, each of which is provided with a port facing in the direction of rotation of said hub, comprising a cup-shaped member secured to said hub and having portions of the wall thereof cut away for receiving said sockets and forming pockets adjacent the ports therein.

45. 5. An air collector for forcing air through an airplane propeller having openings along the trailing edge and a hub portion provided with radially extending sockets each of which has an opening therein and facing in the direction of travel of the plane, comprising an annular member having a trough therethrough for receiving said sockets, and provided with ports registering with the ports in said sockets, and means for collecting the air on said member and directing it into said ports.

60. 6. An air collector for forcing air through an airplane propeller having a hub portion provided with radially extending sockets each of which has an opening therein facing in the direction of travel of the plane and a propeller blade for each socket provided with a port registering with the port in the socket and an opening along the trailing edge, comprising an annular member having ports reg-

istering with the ports in said sockets, a wall extending from the periphery of said member forming a pocket for receiving air and directing it through said ports, and means depending from said member for securing the member to said sockets.

70. 7. An air collector for forcing air through an airplane propeller having openings along the trailing edge and a hub portion provided with radially extending sockets each of which has an opening therein facing in the direction of travel of the plane, comprising a member having a trough formed therein, said trough having a plurality of openings therein for receiving the end of said hub and registering with the ports in said sockets, a wall extending from the periphery of said member for collecting air on said member and directing it through said ports, and means for securing said member to said hub.

75. 8. An air collector for forcing air through an airplane propeller having a series of openings along the trailing edge and a hub portion provided with radially extending sockets each of which has an opening therein, facing in the direction of travel of the plane, comprising a member having a series of openings therein, for receiving the end of said hub and for registering with the ports in said sockets, a wall extending from said member for collecting air therein and directing it through said ports, legs depending from said member, and means extending through said legs for securing said member to said hub.

80. 9. An air collector for forcing air into an airplane hub having radially extending sockets extending therefrom, each of which is provided with an opening through the wall thereof, comprising a member having a series of openings therein, one of which is adapted to receive the end of said hub while the others register with the openings in said sockets, means for collecting air on said member, and means for securing said member to said hub.

85. 10. An air collector for forcing air into an airplane hub having radially extending sockets extending therefrom, each of which is provided with an opening through the wall thereof, comprising a member having a hub-receiving portion formed therewith, troughs in said member for receiving the sockets and having openings therein registering with the openings in the sockets, a wall around the periphery of said member for collecting air on said member, and means extending through the hub-receiving portion for securing said member to said hub.

90. 11. In a propeller, in combination, a hub, radially disposed sockets extending from said hub, each of which has a port formed therein, a hollow propeller blade for each of said sockets having a port in the shank thereof of registering with the port in said socket and a series of slots along the trailing edge thereof, and a member secured to said hub

for collecting air therein and directing it through the registering ports into said blade where it is exhausted through the slots along the trailing edge thereof.

12. In an airplane propeller, in combination, a hub, radially disposed sockets extending from said hub, each of which has a port formed therein, a hollow propeller blade for each of said sockets having a port in the shank thereof registering with the port in said socket and a series of slots along the trailing edge thereof, a member secured to said hub having ports registering with the ports in said sockets for collecting air therein and forcing it through said blades and exhausting it along the trailing edges thereof.

13. In a propeller, in combination, a hub, a series of radially disposed sockets extending from said hub each having a port formed therein, a hollow propeller blade for each of said sockets having a port in the shank thereof registering with the port in said socket and a series of slots along the trailing edge thereof, and a cup-shaped air collector secured to the hub for directing air through the registering ports into said blades and causing it to be discharged along the trailing edges.

14. In a propeller, in combination, a hub, a series of radially disposed sockets extending from said hub, each having a port formed therein, a hollow propeller blade for each of said sockets having a port in the shank thereof registering with the port in said socket and slots along the trailing edge, and a cup-shaped member having the base thereof secured to said hub and having ports registering with the ports in said sockets for forcing air into said blades and discharging it along the trailing edges of the propeller.

15. In a propeller, in combination, a hub having a series of radially extending sockets, each of which has a port formed therein, a hollow propeller blade for each of said sockets having a port registering with the port in said socket and having a series of slots along the trailing edge thereof, and means secured to said hub for positively forcing air into said blades and through the slots along the trailing edges of the blades to decrease the noise of said propeller.

16. In a propeller, in combination, a hub having a series of radially extending sockets, each of which is provided with a port on the leading faces thereof, a hollow propeller blade for each of said sockets having a port registering with the port in said socket and having slots along the trailing edges thereof, and a member secured to said hub and surrounding said sockets forming pockets for collecting air and directing it through said blades.

In testimony whereof I have hereunto subscribed my name this 22nd day of April, 1931.
